UNITED STATES PATENT OFFICE.

WILLIAM POTTER, OF NEW YORK, N. Y.

DOOR.

1,103,377.

Specification of Letters Patent. Patented July 14, 1914.

Application filed January 14, 1913. Serial No. 741,902.

To all whom it may concern:

Be it known that I, WILLIAM POTTER, a citizen of the United States of America, and residing at New York, in the county of New York and State of New York, have invented certain new and useful Improvements in Doors, of which the following is a specification, such as will enable those skilled in the art to which it appertains to make and use the same.

This invention relates to means for maintaining the parallelism of movement of sliding objects, particularly with respect to doors of buildings.

In the usual sliding doors it is customary to provide guiding tracks, either above, beneath, or both, the former requiring an opening in the upper portion of the door frame for the track trucks or rollers, resulting in a very unsanitary dirt collector impossible of access for cleansing, and the latter preventing the continuity of floor coverings, such as carpets and the like, and also resulting in a dust and dirt collector, as well as causing frequent stumbling thereover, and in the use of either the door is frequently dislodged from the track, requiring great strength and sometimes skill to replace the same, and these objectionable features are obviated by means of my present invention.

A further object of this invention is to maintain a sliding door in permanent parallelism with the floor and frame in any degree of opening thereof.

A further object is to mount the door in the frame in such manner as to be readily removed for substitution or repair, without the necessity of calling in skilled mechanics.

A further object is to provide means, in the installation of the door, for truing the same with respect to the frame in the event of a twist or warp in the door.

A further object is to so construct the door as to permit the use thereof either as a sliding or a swinging door, the former being preferably employed when it is desired to close off one room from another, as in winter for the saving of fuel, and to throw two rooms into one, as for social functions or in the summer, when it is desired to have the door out of the way, and the swinging door may be used in the former condition to give quick and easy access to the closed room without the need of sliding the entire door

and connections backward, this being particularly advantageous when the doors are of heavy design.

Instead of the tracks above referred to I provide rack bars which are immovably fixed in a concealed position within the wall recess, thus eliminating the disadvantages of the tracks and also avoiding the marring of the woodwork of the door frame and, in connection therewith, I provide similarly concealed pinions secured to the door or door carrier enmeshed with corresponding rack bars and anchored to each other in any desired manner to prevent independent movement of the pinions, but the racks might be carried by the door or its carrier and the pinions be in fixed relationship with the door frame if desired, to meet varying conditions.

My invention is fully described in the following specification, of which the accompanying drawings form a part, in which the separate parts are designated by the same reference characters in each of the views, and in which:

Figure 1 is an elevation of a door frame and a part of a wall of a room in a building, with the wall partly broken away, and embodying a present preferred form of construction; Fig. 2 is a plan view, taken on the line 2—2 of Fig. 1; Fig. 3 is an enlarged, fragmentary, detail view of the means for maintaining parallelism, taken on the line 3—3 of Fig. 1; Fig. 4 is an enlarged section on the line 4—4 of Fig. 1, and showing a triple-acting bolt which I employ; Fig. 5 is a section on the line 5—5 of Fig. 4, with the door in closed position with respect to the frame; Fig. 6 is a fragmentary, enlarged, view, similar to Fig. 2, but showing an adjusting or equalizing device which I may employ; and Fig. 7 is a section on the line 7—7 of Fig. 6, greatly enlarged.

In the drawings forming a part of this application I have shown a portion *a* of an interior wall of a building, having a space *a*² between the finished surfaces *a*³ and *a*⁴, as is usual, a door frame *b* being arranged in said wall, said frame comprising the uprights *b*² and *b*³ and the lintel *b*⁴ having a groove *b*⁵ arranged longitudinally therein, said door being provided with any suitable trim, but the upright *b*² is provided with a vertical slot between the removable friction strips *b*⁶ and *b*⁷, all of this being of the usual con-

struction for sliding doors, with the exception of the recess b^8 at the outer end of the groove b^5 .

In the present form of embodiment, I provide a door supporting frame within the wall space a^2 and entirely independent therefrom, said frame comprising an inner upright c and two outer uprights c^2 and c^3 adapted to be secured in a concealed position within the said wall space against movement, but in a readily detachable manner, such as by screws or the like to the wall members or to the floor and ceiling, this being governed by conditions, and these uprights are connected together, c and c^2 by means of bars d having racks d^2 thereon, and c and c^3 by means of bars d^3 , thus providing a rigid frame for the support of the door or door carrier.

Horizontally movable within the wall space is a vertical strip e , hereinafter referred to as the door carrier, to which a door e^3 is hinged, as clearly shown, and said door carrier has two pinions e^3 and e^4 rotatably secured thereto by means of a shaft e^5 which anchors the pinions to each other, and brackets e^6 , the pinions being enmeshed with the respective racks d , thus insuring the complementary movement of the said pinions and a positive positioning of the door carrier with respect to the said racks at all times and, in order to insure the permanent enmeshing of the said pinions and racks, I provide cleats e^7 upon the door carrier and slidably engaged with the respective rack bars d , said cleats being preferably provided with rollers e^8 in the upper cleat and e^9 in the lower cleat, the latter to support the weight of the door carrier and the door but, as will be understood, I may connect the said pinions and cleats directly with the door when no door carrier is used, in the event of merely making the door sliding and not swinging.

In Figs. 1, 4 and 5, I have shown a form of bolt which I employ in the event of making the door both sliding and swinging, said bolt being normally in the position shown in Fig. 4 for the sliding door at which time it does not project beyond the door farther than the depth of the groove b^5 , but the bolt f may be moved downwardly, by means of a suitable handle f^2 , pinion f^3 and rack f^4 , so as to be entirely within the door, thus permitting the door to swing open on its hinges, and it may be moved upwardly in order to enter the recess b^8 and thus lock the door in a closed position but, as stated, the normal position is that shown in Fig. 4.

In mounting my door, I remove the friction strips b^6 and b^7 , thus permitting the entry of my door carrying frame into the wall space a^2 , after which the uprights c^2 and c^3 are secured in position, and the friction strips replaced, and the door is ready for use, and this requires no change over

the normal door frame construction, neither does it require any special skill, the only difference being that I provide, if the bolt f is employed, the recess b^8 , and it will be seen that the entire device is just as readily removed for repair or for other reasons and, because of the pinions and racks, the door is always in exact parallelism with the floor of the building, in any position of said door, after having been once properly installed and adjusted, the adjustment in the form so far described being accomplished by the positioning of the uprights c^2 and c^3 . It frequently happens, however, that a door is somewhat twisted or warped, in which event I may employ the device shown in Figs. 6 and 7 at the top of the door carrying frame, in place of the upper bar a^3 , the positions of all the other parts remaining the same, and, in this connection, it will be noted that the upright c is floating, or independent of the wall and door frame, although it does rest upon the floor of the wall space. This device comprises a bar h in permanent connection with the upright c at its inner end and bent at an angle at its outer end to provide a support for three screws h^2 , h^3 , and h^4 , threaded thereinto, the two first being loosely passed through a metal plate h^5 secured in the friction strip b^7 , and the last having a round head resting in a recess h^6 in said plate, an opening h^7 being provided of less diameter than the said recess for the entry of a screw-driver for adjusting the last named screw. When the door is first installed it is adjusted with respect to the slot between the friction strips when in entirely open position and, the bottom necessarily moving true because of the fixed position of the bottom of the door carrying frame, the top of the door, if warped, scrapes against the edge of one or the other of the friction strips, according to the direction of the twist or warp. In order to overcome this it is only necessary to move the top of the upright c in the direction of the twist in the door so that the upper rack bar is at a corresponding inclination to the bottom, as indicated by dotted lines in Fig. 6, thus insuring a proper relationship between the door and the slot between the friction strips at all times regardless of the degree of door opening, and this is accomplished by lengthening or shortening the bar h with respect to the friction strip b^7 , the former being accomplished by loosening the screws h^2 and h^3 and unscrewing the screw h^4 until the proper adjustment is attained, after which the screws h^2 and h^3 are again tightened; in shortening the effective length of the bar h the screw h^4 is turned to the right for a distance and the screws h^2 and h^3 also turned to the right until the proper adjustment is attained, after which the device is again locked by turning the screw h^4 to the

left until it is again tightly seated in the recess h^6 , and in this manner the top of the upright c is moved to the right or left, according to the door twist.

5 While my invention is primarily designed for sliding doors, it will be seen that it renders the combination of both sliding and swinging doors possible, that it is readily mounted in a door frame and as readily removed, that a continual parallelism of movement thereof is assured, that the usual tracks are dispensed with, and that the bolt f accommodates itself to both a door guide and lock, and also to the use of the swinging door, and it will also be seen that I may adjust the direction of movement of the upper part of the door in the degree of any twist or warp in the door.

My invention is very simple, practical, and comparatively inexpensive in installation, and it also permits the dual use of sliding or swinging not heretofore possible except by providing a supplemental hinged door within a sliding door, and, while I have shown a present preferred method of putting my invention into effect, it will be obvious that I am not limited to the exact details shown and described, as various changes in and

modifications thereof may be necessary in order to meet varying conditions and, with 30 a reservation to myself of all such changes as come within the scope of the following claim, what I claim as new, and desire to secure by Letters Patent, is:—

In a wall provided with a door opening, 35 a removable frame, a door carrying strip movable horizontally therein, a door pivoted to said strip, means for maintaining said strip in vertical position, a bar secured to the rear of said frame and extending to a 40 point adjacent said door opening, a plate in the frame of said door opening, a screw therein for drawing said bar toward said opening, and a screw therein for limiting the extent of such bar movement, said screws 45 serving to adjust said door carrying frame to compensate for door warping.

In testimony that I claim the foregoing as my invention I have signed my name in presence of the subscribing witnesses this 50 11th day of January, 1913.

WILLIAM POTTER.
